UNITED STATES PATENT OFFICE.

SAMUEL MANNING, OF ALBANY, NEW YORK.

APPARATUS FOR MIXING FLUIDS.

No. 829,494.

Specification of Letters Patent.

Patented Dec. 25, 1906.

Application filed April 6, 1905. Serial No. 254,117.

To all whom it may concern:

Be it known that I, SAMUEL MANNING, a citizen of the United States of America, and a resident of the city and county of Albany, State of New York, have invented certain new and useful Improvements in Apparatus for Mixing Fluids, of which the following is a specification.

My invention relates to apparatus for mixing fluids; and the object of my invention is to provide a mixing-receptacle by means of which the hot and cold water to be used, especially for bathing purposes, may be mixed, so that the proportion of water from the hot water intake to that of the cold water from the cold-water intake will be accurately determined and when regulated will remain the same until changed by the operator, and such other elements and combinations as are hereinafter more particularly set forth and claimed. I accomplish this object by means of the mechanism illustrated in the accompanying drawings, in which—

Figure 1 is a front elevation with parts broken away. Fig. 2 is a section along the lines W W on Fig. 1. Fig. 3 is a section along the lines X X on Fig. 2. Fig. 4 is a section along the lines Y Y on Fig. 2. Fig. 5 is a section along the lines Z Z on Fig. 1. Fig. 6 is a developed view of the outside of the cylinder B parted at Q on Fig. 3.

Similar characters refer to similar parts throughout the several views.

The casting A is provided with the ports 1, 2, 3, and 4. The port 1 may be the inlet for cold water, the port 2 inlet for hot water, port 3 the outlet for shower-bath, the port 4 outlet for hand-spray.

Within the casting A, I place a plug B, preferably making a tapering ground joint with the interior of the casting A, although I do not limit myself to that arrangement of joint or connection, since it may be cylinder fit or packed, as desired. In the plug B, I provide the openings D, D', and E. The openings D and D' are preferably tapered—that is, wider at one end than at the other, as shown in Fig. 6—in such a manner that when the plug is revolved, so that the opening D or D' registers with either the cold or hot water intakes, the amount of the water admitted will depend upon the position of the opening D or D' which is in register with said intakes.

The port E allows for the discharge through the ports 3 or 4 in the casting A.

The plug B is preferably provided with a

central hub F, Figs. 2 and 5, to which is secured a handle G and a pointer J. The handle and pointer may be secured to the hub in any suitable manner by means of a plate f 60 and bolt g, as shown in Fig. 2, if desired.

I place a cap K, which is preferably provided with boss k, adapted to engage with the front of the plug B, as shown in Figs. 2 and 5, and with a threaded flange K', adapted to 65 engage with threads on the casting A, as shown in Figs. 2 and 5, whereby the cap may be secured in place, the boss engaging the plug forcing the plug to the desired position within the casting and holding it in position 70 there and the cap prevented from turning by means of a set-screw L, Fig. 2. Over the cap I preferably arrange a dial N, which may be secured to the casting A by screws n n, as shown in Fig. 5, or in any suitable manner. 75

It is understood, of course, that the cap K and the dial N are placed in position before the handle G and the pointer J are secured to the hub. On the dial I preferably place the letters "Off," which in Fig. 1 are at the top of 80 the dial and indicate when the pointer J points toward them that no water is admitted into the plug B, the letters "C C" on each side of the word "Off" indicating when the pointer points toward either of them that 85 cold water is delivered to the plug B, the letters "M M" indicating when the pointer points to them that water of medium temperature is delivered to the plug, and the letters "H H" will indicate when the pointer 90 points toward either of them that hot water is admitted to the cylinder.

As thus arranged when the plug B is in the position shown in Fig. 3, the openings D D' therein out of register with each of the intakes 1 and 2, no water is admitted to the plug, and the pointer in this position will be toward the letters "Off." Should the plug be rotated toward the left, the pointer would then move to the position indicated by the letter 100 "C" on the dial, the opening D' would register with the cold-water opening 1, and the cold water would be discharged through the opening E and the shower-port 3. If the plug is rotated from the position shown in Fig. 1 to the 105 right, to the point indicated by "C," the cold water would be admitted to the plug, and the port E of the plug would register with the port 4, and cold water would be discharged through the hand-spray. When the plug is rotated to any position between "C" and "H" 110 (indicated generally by "M") in either direc-

tion, both cold and hot water would be admitted to the plug, and if it was toward the left that the plug had been rotated medium-temperature water would be delivered through the shower, and if toward the right medium-temperature water would be delivered through the hand-spray. When the pointer is rotated to the left in the position indicated by "H," hot water would be delivered to the shower, and if it were rotated to the right to the position indicated by "H" hot water would be delivered to the hand-spray.

I preferably arrange upon the dial the projecting lugs P P', which are stops projecting in the path of the movement of the pointer J and prevent further movement of the pointer, and therefore further rotation of the plug.

By making the openings D and D' narrower at one end than at the other and gradually tapering I have arranged for admitting either a small or a large stream of water and gradually increasing or diminishing the volume when desired by rotating the plug, and it is for this reason that I say that in any position between "C" and "H" both hot and cold water will be admitted, the degree depending upon whether the wide or the narrower portion of the openings D and D' registers with the intakes.

30 In practice I preferably arrange my device so that the cold water will be admitted through the full opening and later on the hot water through the contracted opening and gradually increase the latter and decrease the former simultaneously and at the same time admitting to the shower or to the hand-spray, according to the direction of rotation.

The stops P and P' may be located so that the pointer shall engage them before the hot water is admitted at the full opening, and therefore before the cold is entirely shut off, and thus all danger of scalding may be prevented.

In my arrangement of the mixer the parts 45 are easily removed and readily put together. There is an entire absence of springs and other parts that weaken or deteriorate in their usage. The manner of securing the cap to the casting and at the same time by 50 means of the boss on the cap adjusting the cylinder is a very satisfactory and, I think, novel arrangement.

What I claim as my invention, and desire to secure by Letters Patent, is—

55 1. In a device for mixing fluids; a casting provided with an intake for hot water, an in-

take for cold water, and two outlet-ports; a plug in said casting provided with a port adapted to register with either outlet-ports, which one depending upon the direction the 60 plug is rotated, and also provided with two tapering openings, having the smaller ends of said openings toward each other; a space between the smaller ends of said openings; a space between the ends of the enlarged portions of said tapering openings, whereby the 65 distance remaining between the ends of the tapering openings will allow for the side of the plug between the openings to not only act as a closure for the hot-water intake when 70 the plug is in a single position, but to maintain said hot-water intake closed during a portion of the time the plug is rotated in either direction, the space between the ends of the 75 enlarged portions of said tapering openings sufficiently great to act as a closure for the cold-water port, but which will register with said cold-water port when the plug is rotated in either direction before the hot-water port will be opened; the continued 80 movement of the plug in the direction in which it is rotated causing a decrease in the flow of cold water and permitting the inflow of hot water, dependent upon the extent to which the plug is rotated, until the cold-water 85 intake is closed by the side of the plug between the narrower portions of the said tapering openings, registering with the cold-water port.

2. A device for mixing fluids, comprising a 90 casting; a plug adapted to rotate therein; said casting provided with a hot-water intake, a cold-water intake and two outlet-ports; said plug provided with an opening adapted to register with said outlet-ports, respectively; which one depending upon the direction of rotation of the plug, with gradually-contracted openings adapted to register with the said intakes, all so arranged that by 95 the rotation of the plug in either direction the cold water may be delivered through an outlet-port without interruption, and when the plug is further rotated the amount of cold water will be decreased, and the amount of hot water increased, simultaneously and 100 gradually.

Signed at Albany, New York, this 3d day of April, 1905.

SAMUEL MANNING.
